(57) **CLAIM**

The ornamental design for a housing for a connector, as shown and described.

DESCRIPTION

FIG. 1 is a front elevational view of a housing for a connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a cross-sectional view thereof, taken along line "7-7" of FIG. 1;

FIG. 8 is a cross-sectional view thereof, taken along line "8-8" of FIG. 1;

FIG. 9 is a cross-sectional view thereof, taken along line "9-9" of FIG. 1;

FIG. 10 is a front, top and right side perspective view thereof;

FIG. 11 is a rear, bottom and left side perspective view thereof;

FIG. 12 is a front, right and bottom side perspective view; and,

FIG. 13 is a rear, left and top side perspective view thereof.
